UNITED STATES PATENT OFFICE.

JOHN H. B. BRYAN, OF BUFFALO, NEW YORK.

APPARATUS FOR DRAWING PATTERNS FROM MOLDS.

SPECIFICATION forming part of Letters Patent No. 660,289, dated October 23, 1900.

Application filed January 24, 1900. Serial No. 2,648. (No model.)

To all whom it may concern:

Be it known that I, JOHN H. B. BRYAN, a citizen of the United States, residing at Buffalo, in the county of Erie and State of New York, have invented new and useful Improvements in Apparatus for Drawing Patterns from Molds, of which the following is a specification.

This invention relates to an apparatus for drawing patterns out of sand molds after the latter have been formed in the flasks. An apparatus for this purpose is shown and described in my application for Letters Patent filed November 28, 1899, Serial No. 738,549. The apparatus shown in this former application is more especially designed for lifting small patterns from molds and is mounted in a swinging support, which necessitates carrying the flasks containing the molds from which the patterns are to be lifted to and from the pattern-lifting apparatus. When molding large or heavy patterns, the flasks containing the same cannot be conveniently carried to and from the pattern-lifting apparatus.

One object of this invention is to provide a traveling pattern-lifting apparatus which can be shifted from one flask to another for lifting the patterns therefrom.

Other objects of this invention are to improve the pattern-lifting apparatus in various respects and to provide the same with means for lifting and reversing the flask when the pattern to be molded is attached to a follow-board.

In the accompanying drawings, consisting of two sheets, Figure 1 is a front elevation, partly in section, of the traveling pattern-lifting apparatus, showing the position of the parts preparatory to reversing the molding-flask. Figs. 2 and 3 are fragmentary vertical sections, on an enlarged scale, taken in lines 2 2 and 3 3, Fig. 1, respectively. Fig. 4 is a side elevation, partly in section, of the apparatus, showing the flask reversed. Fig. 5 is a fragmentary front elevation of the apparatus, showing the flask, follow-board, and pattern reversed and the follow-board and pattern lifted from the flask and mold. Fig. 6 is a fragmentary horizontal section, on an enlarged scale, of the air cock or valve which

controls the pneumatic flask-lifting devices, the section being taken in line 6 6, Fig. 1.

Like letters of reference refer to like parts in the several figures.

A A represent two longitudinal main rails, 55 which are supported overhead in the molding-room in any suitable manner, and B represents a wheeled bridge which is mounted on these rails. This bridge consists, essentially, of two horizontal end frames b b, arranged adjacent to the rails A, two transverse rails b' b', connecting these end frames, and flanged supporting-wheels b² b², attached to each end frame and running on the adjacent longitudinal rail A. The bridge is preferably provided with guard-hooks b³, which project underneath the rails, as shown in Figs. 1 and 4, and prevent the bridge from leaving the track.

C represents a transversely - movable carriage which is mounted on the transverse 70 rails b' of the movable bridge. This carriage consists, essentially, of a frame c, arranged above and between the transverse rails b' of the bridge, two pairs of flanged supporting-wheels c' c', journaled on opposite sides of 75 the upper part of the frame c, each pair running on one of the transverse rails b' of the bridge, a post or stem C', depending from the frame c and having near its lower end arms C², which project from the post transversely 80 to the rails b' of the bridge, and two flanged guide-wheels c² c², journaled on the arms C². Each guide-wheel engages against the under side of one of the transverse rails b', between the two supporting-wheels running on the top 85 of the same, thereby forming a triangular bearing of the carriage on each rail b'. These guide-wheels prevent the carriage from being lifted from the bridge. By arranging each of these guide-wheels between its companion 90 supporting-wheels the wheels on the same side of the carriage bear against their rail at three points, whereby the carriage is prevented from rocking on the transverse rail b' in a direction transversely to the main track. 95 The flanges of the wheels on the carriage hold the latter against lateral displacement with reference to the transverse track.

The pattern-lifting apparatus is attached to the carriage C and is constructed as follows: 100

D represents a vertical lifting-cylinder which is secured with its upper end to the lower end of the post C' of the carriage-frame and which is provided at its lower end with a 5 guide-head d.

E is a piston arranged in the cylinder and provided with a depending lifting or piston rod e, which is guided in the lower head d of the cylinder. This lifting or piston rod can 10 be raised by exhausting the air from the cylinder above the piston and can be lowered by gravity upon allowing the air to enter above the piston. This pneumatic means is employed for raising the rod either for lifting 15 the flask or for drawing the pattern from the mold, but it is undesirable for lowering the rod, as the admission of air to the exhausted space above the piston produces a jerky downward movement of the piston and rod.

20 In order to enable the piston and rod to be lowered quickly and with a steady movement, the piston-rod is provided with a manual operating mechanism which is constructed as follows:

25 f represents a gear-pinion secured to a short horizontal shaft f', which is journaled transversely in bearings in the guide-head d. j² is a vertical gear-rack meshing with the pinion and secured to the lifting-rod.

30 f³ is a hand-wheel which is secured to the pinion-shaft and whereby the same is turned. Upon turning the hand-wheel in the direction of the arrow, Fig. 2, the lifting-rod is raised by the pinion, while upon reversing the 35 movement of the hand-wheel this rod is lowered. The lifting-rod may be held against downward movement by a detent-pawl g, which is pivoted on the guide-head d and which can be engaged with the pinion when 40 the rod has been elevated and it is desired to hold the rod in its elevated position.

H represents a cross-head secured to the lower end of the lifting-rod and provided at opposite ends with flask-reversing rollers h.

45 I represents a molding-flask provided on opposite sides with the usual trunnions i, whereby the flask is reversed.

J is the follow-board, which carries the pattern j and which is connected with the flask 50 by pins i', arranged on the flask and entering perforations in the follow-board in a well-known manner. The follow-board may also be attached to the flask, if necessary, by any other well-known means.

55 K K represent loops or endless cords or belts which are hung with their upper bights or portions upon the reversing-rollers h and which are adapted to be engaged with their lower bights or portions around the trunnions 60 of the flask.

The pneumatic means for operating the lifting-rod is constructed as follows: The upper end of the cylinder D is connected with an air-exhausting mechanism. For this purpose 65 a three-way cock M is provided, Figs. 1, 4, and 6, having an inner branch or nipple m,

which connects with the upper end of the cylinder, an intermediate branch or nipple m', connected by a flexible branch tube m² with a main flexible tube m³, leading to the 70 air-exhaust device, and an outer branch or nipple m⁴, which opens into the atmosphere. The rotary plug m⁵ of this cock is provided with a depending actuating-rod m⁶, which is arranged with its lower end in convenient 75 reach of the operator. The lower end of this valve-rod m⁶ is journaled in a bearing m⁷ on the lower head d of the cylinder and is provided with a handle m⁸ for convenient manipulation. Upon turning the plug of the 80 cock M so as to connect the interior of the cylinder with the exhaust-tube the air is exhausted from the cylinder and the piston and the parts connected therewith are raised. Upon turning the plug of the cock M so as to 85 connect the interior of the cylinder with the atmosphere, as shown in Fig. 6, the vacuum in the cylinder is broken and the piston and the parts connected therewith are permitted to descend by gravity. The lower 90 head d of the cylinder is preferably provided with an air-passage d', which permits of the ingress and egress of the air below the piston with sufficient freedom to enable the piston to move freely up and down. 95

For the purpose of permitting the bridge to be moved back and forth on the longitudinal track without disarranging the main exhaust-tube m³ the latter is looped at intervals and the loops are supported by hangers 100 or trolleys N, which run on a rail or track n, arranged lengthwise below one of the main longitudinal rails. As the bridge moves forward this tube is gathered and its loops descend and as the bridge moves backward the 105 tube is extended and its loops rise.

o represents a pneumatic suction cup or holder which is attached to the lower end of the lifting-rod e and which is adapted to be placed upon a pattern or upon a follow-board 110 carrying a pattern. This holder is attached to the pattern or follow-board by exhausting the air from the holder, so that upon raising the holder the pattern or board rises with the same. This holder is provided on its inner 115 side with an elastic bearing rim or flange o', Fig. 3, and is provided at its top with a short pipe o², which is connected to the lower end of the lifting-rod.

P represents a three-way cock having an 120 inner branch or nipple p, which connects with the upper end of the pipe o², an intermediate branch or nipple p', which is connected by a branch pipe or tube p² with the main exhaust-tube m³, and an outer branch or nipple p³, 125 which opens into the atmosphere. Upon turning the plug p⁴ of this cock so that the interior of the holder is connected with the exhaust-tube, as shown in Fig. 3, the holder will attach itself to the surface of the pattern or 130 board upon which it is placed, and upon turning the plug of the valve, so as to place the

interior of the holder in communication with the atmosphere, the vacuum is broken and the holder is released.

In the molding operation the follow-board, 5 with the pattern secured to its upper surface, is placed upon rails, bars, or some other firm and level bed L, which is arranged below the main rails and within reach of the traveling apparatus. The flask is then placed on the follow-board, and the molding-sand is packed into the flask over the pattern and follow-board. When the pattern is to be drawn, the bridge is moved on its track and the carriage on the transverse rails of the bridge as may 10 be necessary to bring the carriage, with its lifting apparatus, over the flask. The lifting-rod and connecting parts are now released by disengaging the pawl g from the pinion, and the latter is turned by the hand-wheel, so as 15 to lower the lifting-rod sufficiently to bring the lower parts of the reversing-cords K near the flask. These cords are now engaged with the trunnions i, as shown in Fig. 1, and upon raising the lifting-rod the flask is raised by 20 the cords from the bed L. The operator now turns or reverses the flask, follow-board, and pattern, so that the follow-board is on top of 25 the flask. During this turning movement of the flask its trunnions roll on the lower bight 30 of the cords or loops and the upper bights move around the rollers of the cross-head. When the flask has been reversed, it is again lowered upon the bed L and the loops are detached from the trunnions preparatory to lifting 35 the follow-board and pattern from the flask. After the flask has been so reversed, as shown in Fig. 4, and the reversing-cords have been detached from the flask the pneumatic holder is lowered upon the follow-board and 40 the plug of the valve P is turned so that the air is exhausted from the holder, whereby the latter is firmly attached to the follow-board. The lifting-rod is now raised by the exhaust 45 device, whereby the follow-board is lifted from the flask and the pattern attached to the follow-board is lifted out of the sand mold in the flask, as represented in Fig. 5. When the follow-board, with the pattern, has been removed from the flask, the board is detached 50 from the holder by turning the plug P, so as to break the vacuum in the holder.

The lower part of the branch pipe p^2 is preferably rigid and guided during its up-and-down movement with the lifting-rod in an eye 55 p^5 , secured to the lower head of the cylinder.

When the pattern is not placed upon a follow-board, but is exposed in the upper part of the flask, the pneumatic holder is applied directly to the pattern.

60 The bridge and carriage are readily moved to bring the lifting apparatus over any flask which is arranged in the molding-room within the area covered by the track on which the bridge travels, thereby making the lifting apparatus available for use in drawing the pat-

terns from flasks located in different parts of the molding-room.

I claim as my invention—

1. In an apparatus for drawing patterns from molds, the combination with a bridge 70 movably mounted on a longitudinal overhead track, of a carriage which is transversely movable on said bridge, a vertically-movable lifting device secured to said carriage and depending therefrom, and a suction-holder arranged at the lower end of said lifting device and adapted to be attached to a pattern, substantially as set forth. 75

2. In an apparatus for drawing patterns from molds, the combination with a horizontally-movable carriage, of a vertically-movable suction-holder mounted on said carriage, an exhaust-tube connected with said holder, and movable hangers which support said tube at intervals, substantially as set forth. 80 85

3. In an apparatus for drawing patterns from molds, the combination with a cylinder, and the lifting piston and rod arranged therein, of a suction-holder attached to said lifting-rod, and exhaust-tubes connected with said 90 lifting-cylinder and suction-holder, substantially as set forth.

4. In an apparatus for drawing patterns from molds, the combination with a vertical cylinder, a piston arranged in the cylinder, 95 and a suction-holder connected with said piston by a lifting-rod, of a main exhaust-tube having branches which connect with said cylinder and said holder, and controlling-valves arranged in said branches, substantially as 100 set forth.

5. In an apparatus for drawing patterns from molds, the combination with a lifting-rod provided with a suction-holder, of a pneumatic means and a manual means for operating said rod, whereby the rod can be raised by the pneumatic means for drawing the pattern and can be lowered by manual means, substantially as set forth. 105

6. In an apparatus for drawing patterns 110 from molds, the combination with a support having a vertical rectilinear guide, of a lifting-rod provided at its lower end with a suction-holder, a vertical gear-rack attached to said rod and arranged to move vertically in 115 said guide, and a gear-pinion mounted in said support and meshing with said rack, substantially as set forth.

7. In an apparatus for drawing patterns from molds, the combination with a cylinder, 120 a lifting piston and rod arranged therein, a suction-holder attached to said rod and an exhaust-tube connected with said cylinder, of a gear-rack arranged on said rod, and a gear-pinion meshing with said rack, substantially 125 as set forth.

8. The combination with a lifting-rod, of a suction-holder attached to said rod and adapted to be attached to a pattern, rollers supported upon said rod, and loops hung upon 130

said rollers and adapted to be engaged with the trunnions of a molding-flask, substantially as set forth.

9. The combination with a lifting-rod, of a suction-holder arranged on the lower end of said rod and adapted to be attached to a pattern, a cross-head connected with said rod, rollers arranged on opposite ends of said head, and loops hung upon said rollers and adapted

to be engaged with the trunnions of a molding-flask, substantially as set forth.

Witness my hand this 8th day of January, 1900.

JOHN H. B. BRYAN.
